UNITED STATES PATENT OFFICE.

WILLIAM L. CHURCH, OF NEWTON, MASSACHUSETTS.

METHOD OF BUILDING DAMS.

No. 870,866.

Specification of Letters Patent.

Patented Nov. 12, 1907.

Application filed July 25, 1907. Serial No. 385,448.

To all whom it may concern:

Be it known that I, WILLIAM L. CHURCH, of Newton, in the county of Middlesex and State of Massachusetts, have invented certain new and useful Improvements in 5 Methods of Building Dams, of which the following is a specification.

This invention relates particularly to what are known as hollow reinforced concrete dams, which are constructed by forming concrete with suitable reinforcing 10 material in the location to be occupied by the dam, suitable molds or forms being employed.

Under the ordinary methods of constructing dams of solid masonry, a necessary procedure is to unwater say one half of the river bed at a time by means of a coffer 15 dam from which the water is pumped out. As this coffer dam is necessarily permanent throughout the whole work of construction, it must be made high enough and strong enough to withstand all expected floods occurring during a relatively long period of construction. The coffer dam is therefore expensive and the time of building it necessarily consumes the most 20 advantageous period of the year for construction; namely, the period of extreme low water. The expense of coffer dam being so great, the tendency is to minimize the cost and take chances on the floods. As a 25 result it happens in a large proportion of cases that floods of unexpected severity occur during the progress of the work, over-topping and damaging the coffer dam and necessarily suspending work on the main construction often involving a great deal of damage to the latter.

The object of my invention is, first, to minimize the prime cost of the coffer dam by making its use apply only to the initial stages of the permanent construction; 30 second, to shorten the time lost in the construction of the coffer dam, thereby enabling the permanent work to be undertaken and pursued during the most favorable season, and third, to make it substantially impossible that even if a flood should occur, the permanent work shall be stopped or seriously interfered with or any resultant damage involved. The general effect 35 of my invention therefore is to greatly lessen the risks attendant upon hydraulic work, and greatly expedite the time of its completion, all of which tend to a material reduction in cost.

In carrying out my invention, I proceed first to build a light temporary coffer dam so as to unwater some portion of the river bed, but said coffer dam, being intended only to protect the permanent work for a short time in 40 its initial stages, is made very light and inexpensive so that if accidentally overtopped no considerable outlay for repair is involved. On a certain class of foundations a coffer dam may be dispensed with altogether and an individual caisson substituted, one for each pier.

Having unwatered some portion of the river or the site of a single pier by either of the above methods, I

proceed to build the footing course of the future buttresses up to a certain height, as, for instance, three feet above the ordinary level of the water, which footing course I may, for convenience, call a pier. I do 60 not build the dam above this stage at all until these piers are all in position across the entire width of the river. The building of these piers involves relatively a very small amount of labor, as they are simple in form and contain but a small amount of concrete. 65 This part of the work can therefore be pushed quickly to completion, and when completed the coffer dam may be at once removed or allowed to float away without chance of future damage to the work. Assuming that the coffer dam has been removed or carried away, 70 I then have a series of isolated pier bases arranged like stepping stones across the whole river, forming the base sections of the future buttresses, or the said bases may be termed the skeleton base of the dam. The subsequent work of building the upper works or 75 the major portion of the dam, including the main portion of the deck, the crest and the apron, above this line can therefore be carried on by temporary scaffolding laid on the piers and at the same time be entirely free from danger of floods. The water of the river runs 80 through between the piers at all ordinary stages without interrupting the work going on above it, said piers being separated by unobstructed water courses. The entire width of the river is obstructed only in the ratio which the thickness of the piers bears to the distances 85 between centers of piers. Even an excessive flood will cause no greater harm than to temporarily suspend operations, but a flood which would rise to great heights when compressed into one half of the river by the ordinary coffer dam method, will rise to only a 90 very moderate height when allowed to flow freely between all the piers without sensible interruption. Having completed the dam above the skeleton base with the water still flowing through underneath the upper works, I select a favorable time of low water, 95 and close the successive openings one after another until the river is compressed into as few openings as will take care of it when running, say, one half full. These final openings are then simultaneously closed in any suitable way. I prefer in closing the said openings 100 to successively add extensions to the completed portion of the deck, the said extensions being carried downwardly between the pier bases. I prefer to employ, in closing the openings between the pier bases, the method and construction represented in Letters 105 Patent of the United States, No. 781,871, dated February 7, 1905, although the invention is not dependent upon the method adopted for closing the dam, either as to its successive openings or the final closing, but relates solely to the method of constructing the dam 110 without danger of interruption of the operation from water.

Of the accompanying drawings forming a part of this specification,—Figure 1 represents a perspective view illustrating my improved method of building a concrete dam. Fig. 2 represents a section on line 2—2 of Fig. 1. Fig. 3 represents a view similar to Fig. 2, showing the deck of the dam extended downwardly to close the openings between the pier bases represented in Fig. 2.

Referring to the drawings, *a a* represent the pier bases, which are built independently of each other on the bed of the stream or on an especially prepared foundation, the said pier bases being erected to a point above the ordinary level of the water, and constituting a skeleton base, between the members of which the

water of the stream is adapted to flow freely
b represents the deck of the dam, *c* represents the crest, and *d* represents the apron, these parts being of reinforced concrete, and collectively forming a hollow shell.

20 The deck, crest and apron are preferably supported by extensions *a'* of the piers, said extensions being built upon the piers, and having their edges formed to correspond to the contour of the inner sides of the deck, crest and apron. The deck, as first constructed, extends from the upper portions of the pier bases to the crest, the lower portion of the deck, as thus constructed, being extended outwardly to form a horizontal ledge or shelf *b'*, in which are openings *b* coinciding with the spaces or water courses between the pier bases, the ends 25 of said openings registering with vertical grooves *b* formed in the sides of the pier bases. After the completion of the upper works formed by the pier extensions *a'*, the deck, the crest and the apron,—the water courses between the pier bases and the upper

works are closed successively by building downwardly-extending deck extensions *b* of reinforced concrete, said extensions engaging the openings *b* and the grooves *b*, and being built between temporary forms applied in the manner set forth in said Letters Patent, No. 781,871

35 As above indicated, my invention is not limited to the construction and mode of operation here illustrated and described for closing the openings between the pier bases and below the upper works, and the successive closure of said openings may be accomplished 40 in any other suitable way and by any other suitable means.

I claim:—

1. The method hereinbefore described of building a dam, the same consisting in building a skeleton base composed 50 of a series of isolated piers separated by unobstructed water courses, then building on said skeleton base above the said water courses, the upper works of the dam, and then completing the base by successively closing the spaces between the piers below the upper works.

2. The method hereinbefore described of building a dam, the same consisting in building a skeleton base composed of a series of isolated piers extending crosswise of the dam, and separated by unobstructed water courses, then extending said piers upwardly to form buttresses, then building the upper portion of the deck and the crest of the dam on said piers and buttresses, leaving the water courses unobstructed, and then completing the base by successively adding extensions to the deck, said extensions closing the spaces between the piers.

55 In testimony whereof I have affixed my signature, in presence of two witnesses.

WILLIAM L. CHURCH
